UNITED STATES PATENT OFFICE.

WILLIAM S. AUNGST, OF ALLIANCE, OHIO.

TELEPHONE-SUPPORT.

No. 895,833.

Specification of Letters Patent.

Patented Aug. 11, 1908.

Application filed May 10, 1907. Serial No. 372,991.

To all whom it may concern:

Be it known that I, WILLIAM S. AUNGST, of Alliance, in the county of Stark and State of Ohio, have invented certain new and useful Improvements in Telephone-Supports; and I do hereby declare the following to be a full, clear, and exact description of the invention, such as will enable others skilled in the art to which it appertains to make and use the same.

My invention relates to an improvement in desk attachments for supporting portable telephones, the object being to provide a support capable of being elevated or lowered, moved toward or away from the supporting standard, or turned to the side, thus enabling the telephone transmitter to be moved to and positively held in any position within the range of various adjustments of the holder.

My invention consists in the parts and combinations of parts as will be more fully described and pointed out in the claims.

In the accompanying drawings, Figure 1 is a view in elevation of my improvement, the sections of the bracket being shown closed up in full lines and distended in dotted lines. Fig. 2 is a view in section through same, and Fig. 3 is an enlarged view showing the sliding and clamping connection between the upright standard and the bracket.

1 represents a metal rod or standard, secured at its lower end to a suitable base 2, which in the present instance, is a clamp 35 having a thumb screw 3 for its movable attachment to the edge of a desk, the standard 1 being secured in the socket 4 at the upper end of the clamp by the screw 5.

The standard 1 may be angular or cylindrical in shape and of a length sufficient to permit of all reasonable and necessary vertical movement of the bracket carrying the telephone transmitter. This horizontal bracket is made in sections, preferably four, the inner end one 6 of which is provided near its rear end with a vertical opening 7 of a size slightly greater than the cross section of the standard so as to permit of the free vertical movement of the bracket on the standard, and at the same time, act as a clamp for sustaining the bracket in any horizontal adjustment at which it may be placed on the standard.

As the opening through the section 6 is but slightly greater than the diameter of the standard, it will be seen that the weight of

the bracket falls on the rear upper edge and the front lower edge of the wall of the opening 7, which edges biting against the standard, act as a clamp and sustain the bracket 60 in position against accidental displacement. The greater the weight on the bracket, the greater the clamping action, hence in order to adjust the bracket vertically it is simply necessary to grasp the bracket and lift same 65 sufficiently to take the weight off the clamping edges of the wall of the opening through section 6 of the bracket, which leaves the latter free to be elevated or lowered, and when the bracket is released its clamping 70 edges will hold it in the position to which it has been adjusted.

In the present instance I have shown the rear end of the section 6 closed by a solid block the latter having the opening 7 for the 75 standard 1, but it is evident that the opening may be directly through the tube constituting section 6 of the bracket. This bracket is made up of a series of telescopic sections 6, 8, 9 and 9^a made of metal, the sections 6, 8 and 9 80 being tubes and the other either of tubing or solid metal. Each section 8 and 9 is provided with a longitudinal groove 10 closed at its inner end, and engaged by stops 11 carried respectively by the sections 6 and 8, the stop 85 11 in section 6 engaging the groove in section 8 and the stop 11 carried by section 8 engaging the groove in section 9. These stops and grooves prevent any rotary movements of the sections and limit their outward movements. The outer section 9^a of this extensible bracket is slotted to receive a pin carried by section 9 and is bent downwardly, rearwardly and outwardly forming the foot 12 on which the telephone transmitter rests. Secured to the foot 12 is the Y-shaped clamp, having two toes 13 adapted to overlap or engage the base of the transmitter at two points; the latter being engaged at a third point by the rearwardly bent portion of the 90 section 9 of the bracket. The stem 14 of the clamp is provided with an elongated slot having its upper walls beveled to receive the beveled head 15 at one end of a screw 16 passing through the foot 12. A wing-nut 17 is 95 screwed on the lower end of the screw 16 and engages the under face of the foot 12. By this arrangement the clamping toes 13 may be adjusted to suit bases of different sizes and clamp them securely to the bracket. With a 100 bracket thus constructed a telephone transmitter may be supported at any convenient 105

height to suit the user, and the bracket may be manipulated to carry the transmitter out of the way, or bring it into any position most convenient for the user.

5 While I have described the improvement as a support for a telephone, it is clearly evident that the bracket may support a tray or tool rack or an electric lamp, and when the standard 1 is made cylindrical in cross-section, as shown in Fig. 1, the bracket can be rotated or turned thereon so as to carry the telephone, tray, etc., out of the way.

Having fully described my invention what I claim as new and desire to secure by Letters-Patent, is,—

1. A desk attachment for supporting a portable telephone, comprising a standard, means for sustaining said standard in an upright position, a bracket movable on the standard and provided near one end with a hole for the accommodation of the standard said hole having slightly greater diameter than the diameter of the standard, and means at the free end of said bracket to receive and support a telephone, whereby the weight upon the free end of said bracket will slightly

incline said bracket and cause it to be retained in position on the standard by frictional contact with the latter.

2. The combination with a standard and means for securing same in an upright position, of a bracket made up of telescopic sections, the free end of one end section having an opening transversely through same for the passage of said standard and the free end of the other end section terminating in a foot, and clamping means on said foot for clamping a telephone to said foot.

3. The combination with a standard, of a horizontal bracket vertically adjustable thereon, and made up of telescopic sections, means for limiting the movements of said sections, a telephone support carried by the outer end section of said bracket, and means for clamping the telephone in said support.

In testimony whereof, I have signed this specification in the presence of two subscribing witnesses.

WILLIAM S. AUNGST.
